(57) **CLAIM**

The ornamental design for a support body for a sail-propelled vehicle, as shown and described.

DESCRIPTION

FIG. 1 is a perspective view of the support body for a sail-propelled vehicle;

FIG. 2 is a front end view of the support body of the present invention;

FIG. 3 is a rear end view of the support body of the present invention;

FIG. 4 is a side elevational view of the support body of the present invention;

FIG. 5 is an opposite side view of the support body of the present invention;

FIG. 6 is a top view of the support body of the present invention; and,

FIG. 7 is a bottom view of the support body of the present invention.
